UNITED STATES PATENT OFFICE.

EMIL WIRTH, OF WAUKOMIS, OKLAHOMA.

FASTENING-BRACKET FOR THE MITERED ENDS OF TIMBERS OR THE LIKE.

1,352,335.

Specification of Letters Patent. Patented Sept. 7, 1920.

Application filed February 17, 1919. Serial No. 277,570.

To all whom it may concern:

Be it known that I, EMIL WIRTH, a citizen of the United States, residing at Waukomis, in the county of Garfield and State 5 of Oklahoma, have invented new and useful Improvements in Fastening-Brackets for the Mitered Ends of Timbers or the like, of which the following is a specification.

The present invention has reference to a 10 means for connecting the mitered ends of timbers or the like.

The primary object is to construct a corner bracket from a single piece of metal shaped to provide right angularly disposed 15 pairs of arms and an angle connecting portion therefor, the said arms receiving therebetween timbers or the like which are secured to the said pairs of arms, and the mitered ends of the said timbers contacting 20 with or resting against the angle connecting portion for the pairs of arms.

The drawings illustrate a satisfactory embodiment of the invention reduced to practice.

25 In the drawings:—

Figure 1 is a side elevation illustrating two timbers having mitered ends connected by the improvement.

Fig. 2 is a similar view but showing the 30 manner in which two of the parallel arms may be bent at the edges thereof to embrace therebetween a rounded timber.

Fig. 3 is a view of the blank from which the fastening element is constructed.

35 Fig. 4 is a perspective view of the fastening means *per se*.

Fig. 5 is an approximately central vertical longitudinal sectional view through the construction illustrated in Fig. 1.

40 The timbers or plates which are to be connected by the improvement have beveled or mitered ends. In Fig. 1 of the drawings both of the timbers 5 and 6 are square or rectangular in cross section, while in Fig. 2 45 of the drawings the timber 6 is round in cross section.

As disclosed in Fig. 3 of the drawings, the means for connecting the timbers is struck from a blank of metal, and comprises 50 a body portion 3 which has angle portions 2 formed at the edges thereof. The portions 2 are designed to be bent on the score lines 8 which are in a line with the edges of the body, to provide spaced parallel arms, and 55 the body is designed to be bent at the points

9 and 10 to also provide parallel arms, the said arms being arranged at a right angle with respect to the arms 2, while the portion 11 of the body, between the opposed pairs of arms, is disposed at an angle corresponding to the pitch of the beveled or mitered ends of the timbers of plates 5 and 6. The pairs of coöperating arms are provided with bolt openings 4, and the timbers 5 and 6 are provided with similar bolt openings. 60

65 By reference to Figs. 1 and 2 of the drawings, it will be seen that the arms 2 are arranged upon the sides of the timber 5, and that the arms 3 are arranged on the upper and inner faces of the timber 6. 70

In Fig. 2, the timber 6 is round in cross section, and therefore I have curved the edges of the arms 3 to correspond with the shape of the said timber. Passing through the openings 4, in the arms and through the 75 timbers are bolts 6', which are engaged by nuts 7.

70 From the foregoing description, it will be seen that the arms of the fastening means engage the right angularly opposed faces or sides of the respective timbers 5 and 6, and that the wall 11 provides an abutment for the mitered or beveled ends of the said timbers. 80

Having thus described the invention, what 85 I claim, is:—

1. A corner bracket for connecting the mitered ends of timbers or the like, comprising right angularly arranged pairs of spaced arms which receive therebetween the timbers and to which the said timbers are secured, and an angle connecting portion for the arms against which the mitered ends of the timbers contact. 90

2. A bracket for connecting the confronting mitered ends of timbers or the like; comprising a member struck from a blank of metal and shaped to provide right angularly disposed pairs of parallel arms which receive the timbers therebetween and 100 are secured thereto, the connecting wall between the pairs of arms being disposed at an inclination corresponding to the pitch of the mitered ends of the timbers and receiving such ends thereagainst and one pair of 105 the arms having their faces disposed in a line with the edges of the second pair of arms.

In testimony whereof I affix my signature.
EMIL WIRTH.
